[57] CLAIM

The ornamental design for container divider, as shown and described.

DESCRIPTION

FIG. 1 is a perspective view of the container divider showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view of a container divider showing a second embodiment of my new design, having an appearance identical to that of the first embodiment except for the absence of a base member; and,

FIG. 9 is an environmental perspective view of the container divider of FIG. 1.

The broken line showing of a container in FIG. 9 is for illustrative purposes only and forms no part of the claimed design.
